UNITED STATES PATENT OFFICE.

MATTHIAS BROCK, DECEASED, LATE OF BOSTON, MASSACHUSETTS, BY EDWARD L. BROCK, ADMINISTRATOR, OF BEVERLY, MASSACHUSETTS, ASSIGNOR TO UNITED SHOE MACHINERY CORPORATION, OF PATERSON, NEW JERSEY, A CORPORATION OF NEW JERSEY.

WORK-POSITIONING MECHANISM FOR UPPER-FORMING AND OTHER MACHINES.

1,419,213.

Specification of Letters Patent. Patented June 13, 1922.

Application filed January 27, 1919. Serial No. 273,453.

To all whom it may concern:

Be it known that MATTHIAS BROCK, deceased, late of Boston, in the county of Suffolk and State of Massachusetts, invented 5 certain Improvements in Work-Positioning Mechanism for Upper-Forming and Other Machines, of which the following description, in connection with the accompanying drawings, is a specification, like reference 10 characters on the drawings indicating like parts in the several figures.

This invention relates to machines for operating on boots and shoes; and is herein shown and described as embodied, for the 15 purpose of explanation, in an upper forming machine of the type shown, for example, in United States Letters Patent Nos. 1,197,437 and 1,197,439, granted Sept. 18, 1916, and No. 1,361,960, granted Dec. 14, 1920, upon 20 applications filed by Matthias Brock, such machines being designed for shaping or molding the upper materials, including the heel stiffener, at the rear portion of a shoe to the sides of a metal form corresponding 25 to the heel end of the shoe and for inwardly flanging the marginal portion of the stock over the edge of the bottom of said form as a step preliminary to the lasting operation, or in cheap grades of shoes, as a substitute 30 for the forming portion of the lasting operation.

As previously constructed or proposed, however, upper forming machines of the described type have not embodied shoe supporting 35 and positioning mechanism adapted to take the shoes on their lasts, since no provision has previously been made to adapt the supporting and positioning means for accommodation to the variations in length and 40 height of lasts and to the spring or pitch of the last bottom.

One of the objects of the present invention is to provide a last and shoe supporting and positioning mechanism which is adapted for 45 use in a machine of the described type to enable the shoe uppers to be formed directly on their lasts. It will be recognized, however, that in some of its novel aspects the invention is not limited to machines of that 50 type nor to means for positioning shoes on the last.

With the above and other objects in view,

a feature of the invention consists in the combination with means for operating on a shoe, of novel means for positioning and controlling a shoe in its relation to such operating means. In accordance with the illustrative embodiment of the invention, the last and shoe supporting means is arranged for movement from a work receiving position to a position to present the shoe to the mechanism which operates upon the shoe, said means being also mounted for preparatory movement with the shoe and last to a position in which the shoe is in a plane to 65 co-operate with said mechanism, means being provided which are effective to lock the supporting means against movement from said plane prior to the presentation of the shoe for the operation of said mechanism. 70 The illustrative forming machine organization is also provided with treadle controlled power means for moving the last and shoe lengthwise into position for the operation of the forming mechanism, this means being 75 yieldingly operated to adapt the mechanism to different sizes of lasts and the consequent variation in the extent of movement required to draw the last into co-operative relation to the forming devices. The illustrated controlling mechanism for the last and shoe supporting means is also organized automatically to return the said supporting 80 means to initial work receiving position to receive another last and shoe after a forming 85 operation has been completed.

Features of the invention are also to be recognized in details of construction of the shoe positioning means.

These and other features of the invention 90 will appear more fully from the following description of an illustrative embodiment of the invention considered in connection with the accompanying drawings, and will be then pointed out in the claims; 95

In the accompanying drawings:

Fig. 1 is a view in side elevation of an upper forming machine of the described type embodying the present invention, parts of the last and shoe positioning mechanism being shown in section; 100

Fig. 2 is a perspective view of part of the last and shoe positioning mechanism, taken from the opposite or rear side of the front

portion of the machine shown in Fig. 1, parts being broken away to disclose interior mechanism;

Fig. 3 is a fragmentary detail perspective view from the same side of the machine as Fig. 1 showing the controlling means for the lock for the heel support; and

Fig. 4 shows a detail of the mechanism controlling the heel pin standard.

10 As pointed out in said prior patents, the forming machine comprises a plurality of duplicate units built into one machine so that a plurality of shoe uppers may be operated upon at the same time. It will suffice 15 to describe the present invention in connection with one of said units.

The upper shaping mechanism comprises a multi-part heel-embracing mold 4 shown in dotted lines in Fig. 1, and backwardly 20 into which the work is carried, and heel embracing wipers 6, also shown in dotted lines in Fig. 1.

The machine is power driven, being controlled by a foot treadle 10 connected with 25 a one-cycle clutch 12 on a shaft 13 driven through a continuously rotated pulley. This power operated driving shaft 13 imparts movement through gearing and under control of the clutch to the cam shaft 14 30 which operates through a lever 15, a rod 16 and a work carrier 18 to draw the work back into the heel-embracing mold 4, the connection between the lever and rod, in accordance with the present invention, including 35 a yielding element, as shown, a lever-connected plunger 19 operating against a coiled spring 20 housed in a tubular portion 21 formed at the rear end of rod 16, and operating to position lasts of different sizes 40 and lengths in co-operative relation to the mold and wipers. When the work carrier 18 has been drawn back, as described, a cam 45 operating against a roll on a lever 22, acts through link 23 to straighten toggle 24 and close the heel embracing mold 4 upon the work presented by carrier 18. The wipers 6, which are operated by a clutch controlled eccentric 25 on a counter shaft 26 geared to a driving shaft 28 continuously rotated by a 50 pulley 30, are then caused to operate through a cam on shaft 14 which acts against a roll carried by a pivoted arm 32 to which the lower end of a rod 34 is connected, the upper end of this rod carrying a laterally offset plate 36 effective, when the rod is depressed by said cam, to move an arm 38 latching the wiper eccentric clutch in inoperative position. The clutch is thrown in when said arm is moved and is effective to 60 reciprocate the wipers continuously to shape the inturned flange of the upper by repeated rubbing movements forth and back over the flange. After the mold 4 has been closed and the wiper clutch latch released, the cam shaft 14 comes automatically to rest. When

the upper has been sufficiently wiped the treadle 10 is again actuated and the wiper clutch is withdrawn with the wipers opened, the heel embracing mold is opened, and the work carrier is moved away from said mold, 70 the parts returning to the starting positions shown in Fig. 1.

The mechanism and organization thus far described, with the exception of the yielding connection 19, 20, 21 for the work carrier, is 75 like that more fully shown and described in said prior patents and the present invention is not concerned with the details thereof.

The last and shoe supporting and positioning means of the present invention comprises a suitable base such as the carrier member 18 arranged for movement into co-operative relation to the devices for operating upon the last and shoe in the manner above described. The rear or inner portion 85 of this base 18 is formed with an upstanding casing 40 housing the heel pin standard and its operating parts and the front or outer end of the base is provided with an upstanding tubular holder 42 for the standard supporting the toe rest, which holder is provided with a laterally offset horizontal extension or plate 44 (Fig. 2) connected thereto by a fin 43.

The housing 40 is provided at its upper 95 end with a tubular guide 46 vertically aligned with a bore formed in the base 18 and in which the flattened shank of the heel supporting standard 48 slides. This standard is supported from the base 18 as follows. The 100 base, as previously stated, has a vertical bore aligned with said shank. In this bore is slidably mounted a plunger 50 having a pin and slot guiding and movement-limiting connection with the base and having a reduced upper end projecting above the base and slotted. A squared sleeve or block 52 embracing the projecting end of said plunger rests upon and is supported by the upper 105 face of the base 18 and is slotted in alignment with the plunger slot to permit the end of a controlling lever, later described, to project therethrough and to seat in the slot in the upper end of plunger 50. A plate 54 (see Figs. 2 and 4) is mounted between the 110 walls of housing 40 and is formed at its lower end with a slotted guide block 56 offset toward the rear of the machine and having its base formed with a bore and with a lateral flange 58 engaged by the bent upper 115 end of a stop plate 60 rigidly connected with the sleeve 52. A heavy coiled spring 62 is interposed between the lower face of said guide block and the upper face of sleeve 52 and yielding supports said plate and guide block, upward movement of the guide block being limited by the stop plate 60. Between the upper end of guide block 56 and the lower end of the tubular guide 46 the shank 48 of the heel standard is reduced in thick- 120 125 130

ness, the lower end of this reduced portion sliding in the guide block 56 and being shouldered at 64 and provided below this shoulder with a reduced cylindrical extremity extending through the bore in the base of the guide block. A second and lighter coiled spring 66 is mounted in the guide block 56 between said shoulder 64 and the base of the block and acts yieldingly to support the heel pin standard 48. The plunger 50 is moved upwardly, for a purpose hereinafter described, after the last carrier 18 has been drawn backwardly into co-operative relation to the mold 4 and wipers 6, by a slide 68 with which plunger 50 is aligned when fully drawn backwardly, and which slide is moved upwardly when the connected toggle 70 is straightened by movement of link 72 through a lever 74 fulcrumed on the machine frame and having a roll operating in a cam track as in the machines of said prior patents.

The upper end of standard 48 is enlarged to form a head 76 channeled to receive the base of a heel post 78 in the upper bifurcated end of which a heel pin 80 is pivoted for limited oscillatory adjustment to accommodate itself to the hole in a last 2. The post 78 is adjustable in ways formed in the head 76 lengthwise of the shoe and is held in adjusted position by means of a spring pressed toothed block 82 carried by the head and engaging teeth formed on the base of the heel post. This adjustment is utilized in changing from one class of work to another, as from men's lasts to women's or children's lasts, the permissible yielding of the spring connection 19, 20 in the last moving mechanism being intended to compensate for the differences in length between the heel pin and the extremity of the heel end of the last in different sizes of lasts for the same class of shoes, and the lengthwise adjustment of the toe rest, later described, compensating for the differences in length of shoes.

To hold the heel post standard against upward movement from depressed (operating) position, to condition the standard for downward movement against the heavy resistance of spring 66; and to condition the standard for and automatically to return it to initial raised position after the operation upon the shoe, the following means are provided.

A locking block 104 bifurcated to embrace the plate 54 and loosely pivoted on said plate has its rear end formed with an opening through which extends the shank of the standard 48, opposite side walls of said opening being formed with reverse double bevels best seen in Fig. 2, which, when the block is horizontally positioned, permit free vertical movement of the standard in both directions but which, when the block is tilted on its pivot, prevent up and down movements of the standard rela-

tively to the block in the respective reversely tilted positions of the block. This block is positioned and controlled through connections with a lever 106 having a pivot pin 108 (Figs. 1 and 3) journaled in one wall of the housing 40 and having its rear end inserted through the slot in sleeve 52 and loosely seated in the slotted upper end of plunger 50. At a point between this plunger and the pivot pin 108, the lower end of a rod 110 is pivoted to lever 106 and extends upwardly and loosely through a bore in a pivot block 112 journaled on a pin extending between the arms of the locking block 104 at the front end of the block, one arm of said block being recessed (Fig. 3) to provide space to receive the pivot block. At the upper and lower faces of the pivot block coiled springs 114 of substantially equal strength are sleeved on the rod and abut against washers 116 fixed to the rod at substantially equal distances from the respective faces of the block when the locking block 104 is in neutral or horizontal position. The pivot pin connecting rod 90 110 to lever 106 extends through the lever and at the outer side of the lever carries a roll 118 which extends through a vertical opening in the adjacent wall of housing 40 and abuts against the under face of a laterally offset flange at the top of a bracket 120 which is fastened to the side of the machine frame adjacent to the base 18, this under face acting as a cam and having heel standard controlling inclines 120^a and 120^b at its front and rear ends, respectively, and with an intermediate straight neutral portion 120^c. In the outer position of the base 18 with the supported last and shoe out of co-operative relation to the heel-embracing mold and wipers, the roll 118 rests against section 120^a of the flange, the upper spring 114 being compressed and the locking block 104 being tilted as shown in Figs. 1 and 2 to lock the standard 48 against upward movement from any position to which it is depressed through hand lever 98 as shown in Fig. 1.

Co-operating with the locking block and controlled through connections to the same lever 106, are stop dogs 122 and 124 journaled respectively above and below the locking block 104 on the plate 54 and having block engaging noses 123 and 125 (Fig. 2) respectively. Springs 126-128 anchored to the housing 40 and attached to the ends of these dogs normally tend to swing these noses into position for engagement with the upper and lower faces of the locking block to determine a neutral horizontal position of the block, these respective movements and the positions of the dogs being limited and determined by stop pins 130, 132 carried by plate 54. The upper dog 122 in the position determined by the pin 130 prevents

the block 104 from swinging past a horizontal position from the tilted position in which it is shown in Figs. 1 and 2, and the lower dog 124 in the position determined by the pin 132 similarly prevents the block from swinging past the horizontal from its reversely tilted position in which the standard 48 may move upwardly but can only move downwardly against the resistance of the heavy spring 62 to which the reversely swung block transmits the supporting strain through plate 54 and guide block 56. The members 122 and 124 thus permit such movements of the block 104 from either of its locking positions as may be required to release the standard 48, but prevent the block from tilting so far as to lock the standard in the reverse sense except as permitted by the mechanism which controls said members.

Tilting of the upper dog 122 against the tension of its spring 126 to inoperative position, and the tilting of said dog to operative position through said spring are effected and are permitted respectively by a rod 134 pivoted at its lower end to one side of the forward end of lever 106 and at its upper end sliding freely through a pivot block 136 pivotally mounted on the dog 122 at its end opposite the stop pin 130. The end of the rod projects beyond the pivot block and has a fixed collar 138 thereon spaced above the upper face of the block in the initial fully outdrawn position of the last and shoe carrier 18 and providing for limited downward movement of rod 134 without turning the stop dog 122 from engagement with the pin 30 as the roll 118 on lever 106 is released by the part 120^a of the cam on bracket 120 in the movement of the last and shoe into the heel-embracing mold.

Tilting of the lower dog 124 against the tension of its spring 128 to inoperative position and tilting of the dog through its spring to operative position are effected and are permitted respectively by a rod 140 (Fig. 2) pivoted at its lower end to lever 106 in axial alignment with the pivot of rod 134 of the upper dog, and at its upper end sliding freely downwardly through a bore in a pivot block 142 journaled on a pin extending outwardly from the dog 124 at its end opposite the stop pin 132. A fixed collar 144 on the rod abuts against the under side of the pivot block 142 and holds the dog 124 in inoperative relation to the locking block 104 in the initial fully outdrawn position of the last and shoe carrier 18 and as the carrier is moved rearwardly to cause the portion 120^a of the cam to release the lever 106 to the balancing action of the springs 114 this collar is drawn away from block 142 permitting spring 128 to turn the dog into engagement with the downwardly tilted front end of the locking block.

The toe rest 146 is supported in the tubular holder 42 (forming a rigid extension of the carrier or base 18) for depression, locking, and release and elevation coincidently with the same operations in respect to the heel pin standard. As shown, the toe rest 146 may be of any suitable construction and preferably is formed to permit transverse rocking adjustment to conform automatically to the toe of the shoe in accordance with well known constructions of toe rests. It is provided with a depending spindle 148 freely sliding through the bore of a tubular stem 150 rising from a plate 152 which is slidable longitudinally in ways formed in the upper face of a transversely swinging base 154. The stem 150 has its upper end flanged and embraced by the overlapping edge of a plate secured to the bottom edge of a collar 156, said collar enclosing and confining between it and said flanged end, a nut threaded on spindle 148. This collar 156 is also provided with an upstanding boss through the smooth bore of which the stem 148 freely moves. When the collar is manually turned the nut is turned with it and acts to adjust the stem and toe rest vertically. The plate 152 is retained in longitudinally adjusted position by a set screw 153 fitted in a boss laterally outstanding from the base 154 and engaging the side edge of the plate. The base 154 is pivoted on a boss at the rear end of the laterally extending head 158 of a toe rest supporting standard 160 having a reduced tubular lower portion 162 fitting in the socket of the holder 42 and normally raised in said socket by a coiled spring 164 seated in said tubular portion and engaging at its lower end the base of the socket in holder 42. The front of the head 158 of the toe rest standard is provided with a guiding edge 165 formed as an arc with the pivot of the base 154 as center and serving in co-operation with a spring pressed frictional plug 166 carried by the base and engaging said edge, to hold the base in its transversely adjusted position. It will be evident that after the toe rest and its supporting means have been adjusted to receive a last and shoe positioned on the heel pin 80, the toe rest may be depressed coincidently with the heel pin and against the resistance of the upholding coiled spring 164 at the base of standard 160.

To hold the toe rest standard in depressed position and subsequently to release it, the following mechanism is provided. To the head 158 of the standard is attached the upper end of a depending bar 168 (Fig. 2) which is laterally offset from the standard 160 and holder 42 and is vertically slidable with the standard. This bar slides freely through a correspondingly shaped recess in the horizontal plate 44 offset from holder 42. A locking plate 170 is seated on the

holder 42 and has one edge slotted to embrace the fin 43 and adjacent to said slot is formed with an opening through which the bar 168 may slide. The sides of this 5 opening facing the opposite faces of bar 168 are downwardly and inwardly beveled and are effective, when the front end of the plate is tilted upwardly, frictionally to grip and prevent upward movement of the depressed 10 bar 168 and standard 160 while permitting downward movement of said parts. A coiled spring 172 (Fig. 2) interposed between the front end of the locking plate and a lug 174 offset from the holder 42 normally tilts 15 said plate to a position permitting depression of the bar 168 and its standard but preventing upward movement thereof as described. This tilted position of the locking plate is the normal position of the plate 20 when the carrier 18 is fully outdrawn. The plate is controlled by movement of the carrier 18 as follows:

A link 176 (Fig. 2) is pivotally attached at its upper end to the spring pressed end 25 of the locking plate and has slidably mounted thereon adjacent to its lower end a collar 175 which is pivotally connected to the front end of a controlling lever 178 standing outside of the housing 40 at the side opposite 30 to the heel pin controlling lever 106 and journaled intermediate of its ends on a pin laterally outstanding from the base of holder 42. A nut 177 adjustably mounted on the lower end of rod 176 acts as an abutment 35 engaged by the collar 175 in moving downwardly from the position shown in Fig. 2. The rearward end of lever 178 carries a roll 180 which, in the fully outdrawn position of carrier 18, stands below and slightly forwardly of the front end of a finger 182, which front end underlies the upper horizontally flanged edge 184 of a bracket 186 adjustably fixed to the machine frame adjacent to the front end of carrier 18 as best 40 seen in Fig. 2. This finger is pivoted intermediate of its ends to the rear end of said bracket and has a downwardly bent rear end 183 to which a spring anchored to the bracket is attached. This spring is effective 45 normally to tilt the front end of the finger upwardly against the bracket flange 184 and permits the roll 180, when the carrier is drawn inwardly, to engage the lower edge 50 of the finger and to tilt the rear bent end 55 of the finger upwardly and to ride beyond said finger end which is subsequently pulled down by its spring to a position below the roll.

The pivoted finger, therefore, yields during the rearward or indrawing movement of the carrier to position the last in operative relation to the forming devices and does not act through lever 178 to change the position of locking plate 170. On the reverse or 60 outward movement of the carrier from

working position, the roll 180 rides over the upper edge of the rear bent end of the finger (which cannot yield downwardly since its front end engages the flange 184) and is guided over the top of said flange 70 184, thereby swinging the front end of the lever 178 downwardly until nut 177 is engaged, and thereafter imparting further movement to the lever sufficient to tilt the locking plate 170 against the tension of its 75 spring 172 to release the bar 168 and standard 160 for elevation by the spring 164 of the standard. Thereafter in the continued outward movement of the carrier, the roll passes off the flange 184 and drops to its 80 initial position with the spring of the locking plate tilting said plate as shown in Fig. 2.

From the preceding description it will be evident that springs 62 and 66 of the heel support and the spring 164 of the toe rest initially hold the last seated on the heel pin and toe rest elevated above the plane which they occupy when the last and shoe are in co-operative relation to the forming means. 85 This plane is established by determinately depressing the last and shoe and in holding the last supporting means in the position to which they are depressed. The mechanism for depressing the last and shoe and 90 its supporting means as herein shown, comprises a bracket 84 secured to and upstanding from the top of the machine frame and having a guide 86 outstanding over the heel seat of a supported last in the outer position 100 of the last carrier 18. A vertically movable plunger 88 slides through the guide 86 and has its lower end pivoted to a depressor plate 90 intermediate of its ends, said plate having an upstanding lug 92 at its rear end 105 and having sole engaging feet at its opposite ends. A coiled spring interposed between the plunger and said lug normally tends to hold them separated and a set screw 94 projecting from the lug toward the plunger 110 limits and determines by contact with the plunger the plane into which the heel seat is leveled by depression of the plunger. The upper end of the plunger is connected by a link 96 with a hand lever 98 fulcrumed 115 on the upper end of an upstanding arm 85 on bracket 84 and having a lateral offset adjacent to its fulcrum point which carries an adjustable set screw 100 arranged to engage the arm 85 when the lever is depressed determinately to limit the extent to which the sole on the last 2 may be depressed by the plate 90. The set screw will, of course, be adjusted to aline the sole with the wipers and since the last is yieldingly supported 125 and may be depressed, the set screw 100 will always position the sole in the proper plane for the action of the wipers. A coiled spring 102 connects the hand lever 98 with bracket 84 and normally holds the lever and de- 130

pressor plate elevated above a supported last and shoe.

In the operation of the machine, the hand lever 98 is released when the last and shoe have been depressed to the plane predetermined by the set screw 100, and the operator subsequently depresses treadle 10, starting the machine, the link 16 drawing the carrier inwardly to bring the heel end of the last against and within the embracing mold 4 which is immediately closed and the wipers 6 operated. These wipers, as described in said prior patents and application, are first fully closed over the heel seat of the shoe and thereafter are continuously reciprocated without being fully retracted so that they remain over the sole of the shoe and give a continuous series of rubbing upper flanging and compacting movements until the treadle 10 is again actuated, this actuation resulting in completely retracting and stopping the wipers, opening the heel embracing mold and sliding the last carrier 18 outwardly in the sequence named as fully described in said prior patents.

After the last and shoe have been depressed in the manner described, the locking block 104 in the tilted position indicated in the drawings acts automatically to prevent reverse upward movement of the heel post standard during the rearward movement of the carrier to present the shoe in operative relation to the mold 4 and the wipers, the release of the lever 106 by the part 120^a of the cam simply permitting the springs 114 to assume a balanced relation without affecting the position of the locking block. It will be understood that in this balancing action of the springs the rear end portion of the lever 106 is tilted upward slightly in the slots in members 50 and 52, the front end of the lever having a slight corresponding downward movement which serves through the rod 140 partially to release the stop member 124 to the action of its spring without affecting the position of the upper stop member 122. After the shoe has been clamped by the closing of the mold 4 round the heel end, the slide 68 is moved upwardly, as hereinbefore described, this slide serving to elevate the plunger 50 and through the engagement of the upper end portion of this plunger with the lever 106 to swing the rear end of this lever farther upwardly and through the lower spring 114 to tip the locking block 104 into its reverse locking position, the lever acting simultaneously through the rod 134 to swing the stop member 122 out of its limiting position in such manner as to permit this movement of the member 104 to its reverse position. With the locking block 104 thus tilted reversely from the position indicated in the drawings, the standard 48 is locked against downward movement relatively to said block but is subjected to the control of

the comparatively heavy spring 62 which bears upwardly against the member 56 on which the locking block is supported, in place of the comparatively light tension of the spring 66 against which the standard 70 was moved downward manually, the spring 62 being subjected to increased tension by the continued upward movement of the plunger 50 acting on the sleeve member 52. A more effective yielding support for the 75 shoe against the downward pressure of the wipers is thus afforded.

After the operations on the shoe have been completed and the work is released by the return of the mold and the wipers to starting position, the spring 66 may act to elevate the standard 48, the latter acting by its frictional engagement with the locking block 104 to tilt the block against the light tension of the lower controlling spring 114 to a horizontal neutral position past which it is not permitted to tip by the lower stop member 124 which is still maintained in its operative limiting position. When the plunger 50 is permitted to move downwardly by the retractive movement of the slide 68, the release of the lever 106 permits the springs 114 again to assume a balanced relation. As the carrier 18 starts to move outwardly in its return to starting position, the roll 118, if the locking block 104 has not already assumed a neutral horizontal position in response to the action of the spring 66 on the standard 48, engages the upturned part 120^c of the cam, and the lever 106 is thereby 90 swung in the direction to return the block to such neutral position, the stop members 122 and 124 then being effective at the opposite sides of the block to maintain it in such position as the roll travels along the neutral portion 120^b of the cam. Finally, upon engagement of the part 120^a of the cam with the roll 118, the lever 106 is tipped to its initial position as indicated in the drawings, wherein the lower stop member 124 is tilted 95 out of its limiting position and the locking block 104 is so inclined as to permit downward movement of the heel post standard when the next shoe is mounted thereon and depressed by the action of the lever 98. As 100 above stated, such depression of the shoe is against the tension of the light spring 66, the locking block being turned by its frictional engagement with the standard a sufficient distance to permit the standard to slide 105 through the opening in the block and the movement of the locking block past a neutral position being prevented by the action of the upper stop member 122.

The operation of the means whereby the 125 toe post is locked against upward movement and is subsequently released in time relation to movement of the carrier 18 has already been explained in connection with the description of that portion of the structure 130

and will be clearly understood without further explanation.

Having explained the nature of this invention and described a preferable embodiment thereof, what I claim as new and desire to secure by Letters Patent of the United States is:

1. In a machine of the class described, the combination with mechanism for operating upon a shoe, of last and shoe supporting means movable from a work-receiving position to a position to present a shoe for the operation of said mechanism and constructed and arranged for preparatory movement with the last and shoe to a position in which the shoe is in a plane to co-operate with said mechanism, and means acting automatically in said preparatory movement to lock and hold said supporting means against return movement with its shoe from said co-operative plane prior to the positioning of the shoe for the operation of said mechanism on the shoe.

2. In a machine of the class described, the combination with mechanism for operating upon a shoe, of last and shoe supporting means movable from a work-receiving position to a position to present a shoe for the operation of said mechanism and constructed and arranged for preparatory movement with the last and shoe from a normal position to a different position in which the shoe is in the plane to co-operate with said mechanism, means to lock and hold said supporting means against movement with its shoe from said co-operative plane prior to the positioning of the shoe for the operation of said mechanism on the shoe, and means automatically operative subsequently to cause said locking means to release the shoe for return movement from said plane.

3. In a machine of the class described, the combination with mechanism for operating upon a shoe, of shoe and last positioning means comprising a last and shoe support movable to and from a position to present a shoe for the operation of said mechanism and constructed and arranged for additional movement with a last and shoe from a normal position to a different position in which the shoe is in the plane to co-operate with said mechanism, means to lock and hold said support against movement with the shoe from said co-operative plane, and means automatically operative subsequently to release the locking means and to restore the support to said normal position.

4. In a machine of the class described, the combination with mechanism for operating upon a shoe, of last and shoe supporting means movable from a work receiving position to a position to present a shoe for the operation of said mechanism and constructed and arranged for preparatory movement with the last and shoe from a normal posi-

tion to a different and determinate position in which the supported shoe is presented in a plane to co-operate with said mechanism, means for moving said supporting means to present the shoe in said plane when said means is in work-receiving position, and means to lock said supporting means with the shoe in said plane prior to the positioning of the supporting means with the shoe for the operation of said mechanism. 75

5. In a machine of the class described, the combination with mechanism for operating upon a shoe, of last and shoe supporting means movable from a work receiving position to a position to present a shoe for the operation of said mechanism and constructed and arranged for preparatory movement with the last and shoe from a normal position to a different position in which the supported shoe is presented in a plane to co-operate with said mechanism, means automatically operative to lock said supporting means with the shoe in said plane prior to the positioning of said means with the shoe for the operation of said mechanism, and means automatically operative to release said locking means and to present the supporting means and shoe in their normal initial plane when said supporting means is withdrawn to work receiving position. 95

6. In a machine of the class described, the combination with mechanism for operating upon a shoe, of normally elevated last and shoe supporting means comprising a heel pin and a toe rest arranged for preparatory depression to a position in which the supported shoe is in a plane for the operation of said mechanism on the shoe and movable with the supported shoe from a work receiving position to a position to present the depressed shoe for the operation of said mechanism, and means to lock and hold said supporting means against movement with the shoe from depressed position prior to the positioning of the shoe for the operation of 110 said mechanism on the shoe.

7. In a machine of the class described, the combination with mechanism for operating upon a shoe, of normally elevated shoe supporting means arranged for depression to a position in which the supported shoe is in a plane for the operation of said mechanism on the shoe and additionally movable with the supported shoe from a work receiving position to a position to present the shoe for the operation of said mechanism, and means automatically operative to lock said supporting means in depressed position for the operation of said mechanism and subsequently to unlock and elevate said supporting means 120 and the shoe to their normal position.

8. In a machine of the class described, the combination with mechanism for operating upon a shoe, of a shoe support movable from a work receiving position to a 130

position to present a shoe for the operation of said operating mechanism and constructed and arranged for preparatory depression from a normally elevated position to a position 5 in which the shoe is presented in a plane to co-operate with said mechanism, means movable to depress the support and shoe to said co-operating plane, means operative automatically to lock said support in depressed 10 position prior to the positioning of the shoe for the operation of said mechanism, and means automatically operated in time relation to the operation of said mechanism on the shoe to release said locking means and to 15 restore the support to its normally elevated position.

9. In a machine of the class described, the combination with mechanism for operating upon a shoe, of shoe positioning means comprising a carrier arranged for movement from a work receiving position to a position in operative relation to said mechanism, a shoe support carried by and moving with said carrier and arranged for preparatory 20 movement relatively to said carrier in the direction of the height of the shoe from a normal work receiving position to a different position in which the supported shoe is presented in a plane for the operation of said mechanism on the shoe, and means automatically 25 operative in said preparatory movement to lock said support with the shoe in said operating plane prior to the movement of the carrier, support and shoe to position the shoe 30 for the operation of said mechanism.

10. In a machine of the class described, the combination with mechanism for operating upon a shoe, of last and shoe positioning means comprising a carrier arranged for 40 movement from a work-receiving position to a position in operative relation to said mechanism, a last and shoe support carried by and moving with said carrier and arranged for preparatory movement relatively to the carrier from a normal work receiving position 45 to a different position in which the supported shoe is presented in a plane for the operation of said mechanism on the shoe, and means automatically operative to lock said support against movement from said operating 50 plane prior to movement of said carrier, support and shoe into operative relation to said mechanism and automatically operative subsequently to unlock said support and restore it to normal work receiving position.

11. In a machine of the class described, the combination with mechanism for operating upon a shoe, of last and shoe positioning means comprising a carrier arranged for 60 movement from a work-receiving position to a position in operative relation to said mechanism, a last and shoe support carried by and moving with said carrier and arranged for preparatory movement relatively to the carrier from a normal work receiving position 65

to a different position in which the supported shoe is presented in a plane for the operation of said mechanism on the shoe, means arranged to co-operate with said shoe and said support in the work-receiving position of the 70 support and operative determinately to move the shoe and said support to position the shoe in the plane for the operation of said mechanism, and means to lock said support against movement from said operating plane prior 75 to movement of the carrier, support and shoe to present the shoe for the operation of said mechanism.

12. In a machine of the class described, the combination with mechanism for operating upon a shoe, of shoe positioning means comprising a carrier arranged for movement from a work receiving position to a position in operative relation to said mechanism, a shoe support carried by and moving 80 with said carrier and arranged for additional movement relatively to the carrier from a normal work receiving position to a different position in which the supported shoe is presented in a plane for the operation 85 of said mechanism on the shoe, and means arranged to engage a shoe on said support before the carrier arrives in operative relation to said mechanism and operative determinately to move the shoe and said 90 support to position the shoe in the plane for the operation of said mechanism.

13. In a machine of the class described, the combination with mechanism for operating upon a shoe, of a last and shoe support 100 movable from a work receiving position to a position to present the shoe for the operation of said mechanism and constructed and arranged for additional movement from a normal position to a different position in 105 which the shoe is presented in the plane for the operation of said mechanism on the shoe, means arranged to engage a supported shoe in the work receiving position of said support and operative determinately to move 110 the support and shoe to position the shoe in the plane for the operation of said mechanism, and means for locking said support against movement with the shoe from said operating plane.

14. In a machine of the class described, the combination with mechanism for operating on the bottom of a shoe, of a normally elevated shoe support movable rearwardly to present a shoe to said mechanism, manual means for engaging the bottom of the shoe and depressing the support and shoe to a predetermined position, and means automatically operative to sustain the shoe against the downward pressure of said operating mechanism and for holding the shoe against return forward movement.

15. In a machine of the class described, the combination with mechanism for operating upon a shoe, of a normally elevated 125

- last and shoe support movable from a work receiving position to a position to present the shoe for the operation of said mechanism and constructed and arranged for 5 preparatory depression from normal elevated position to a position in which the shoe is located in the plane for the operation of said mechanism, means arranged to engage a supported shoe on said support in the work receiving position of the support and determinately to depress the shoe and support to position the shoe in said plane, and means automatically operative to lock said support with its shoe against movement from said 10 operating plane, prior to movement of the support and shoe from work-receiving position and automatically to release and elevate said support after the operations on the shoe have been completed.
- 15 20 16. In a machine of the class described, the combination with mechanism for operating upon a shoe, of a work carrier movable from a work receiving position to a position in operative relation to said mechanism, supporting means for the heel end and forepart of a last and shoe mounted on and moving with said carrier and arranged for preparatory movement relatively to said carrier from a normal position to a different 25 30 35 position in which the shoe is presented in the plane for the operation of said mechanism on the shoe, and means to lock said supporting means against movement from said operating plane before the carrier arrives in operative relation to said mechanism.
17. In a machine of the class described, the combination with mechanism for operating upon a shoe, of a work carrier mounted for movement from a work receiving position to a position in operative relation to said mechanism, supporting means for the heel end and the forepart of a last and shoe mounted on and moving with said carrier and arranged for preparatory depression 40 45 relatively to said carrier from a normal elevated position to a position in which a supported shoe is in the plane for the operation of said mechanism on the shoe, means normally tending to elevate said supporting means, and means to lock said supporting means against upward movement from said operating plane prior to the movement of said carrier and supporting means from work receiving position.
- 50 55 60 18. In a machine of the class described, the combination with mechanism for operating upon a shoe, of a carrier mounted for movement from a work receiving position to a position in operative relation to said mechanism, supporting standards for the heel and toe ends of a last and shoe mounted on and moving with said carrier and arranged for preparatory depression from normally elevated positions to positions in which the supported shoe is in the plane for 65 70 75 80 85 90 95 100 105 110 115 120 125 130 the operation of said mechanism on the shoe, and means to lock said standards in said depressed positions prior to movement of the carrier into operative relation to said mechanism.
19. In a machine of the class described, the combination with mechanism for operating upon a shoe, of a carrier mounted for movement from a work receiving position to a position in operative relation to said mechanism, supporting standards for the heel and toe ends of a last and shoe mounted on and moving with said carrier and arranged for preparatory depression from normally elevated positions to positions in which the supported shoe is in the plane for the operation of said mechanism on the shoe, means arranged, in the work receiving position of said carrier, to co-operate with and depress a supported shoe and said standards to position the shoe in said plane, and means to lock said standards against upward movement from depressed position prior to movement of the carrier to present the shoe for the operation of said mechanism and to release said standards after the operations upon the shoe have been completed.
20. In a machine of the class described, the combination with means for operating on the bottom of a shoe, of a normally elevated shoe support movable rearwardly to present a shoe to said mechanism, a manually operative device for engaging the bottom of the shoe and depressing the shoe and support to a predetermined plane and then releasing the shoe, and a locking device automatically operative to retain the shoe support in its depressed position.
21. In a machine of the class described, the combination with mechanism for operating upon a shoe, of a shoe supporting standard movable lengthwise of the shoe from a work receiving position to a position to present the supported shoe for the operation of said mechanism thereon and constructed and arranged for preparatory movement substantially perpendicularly to the plane of the bottom of a supported shoe from a normal position to a second position in which the shoe is in the plane for the operation of said mechanism on the shoe, means normally tending to move said standard to said normal position, and locking means co-operating with said standard and conditioned by return movement of the standard to work receiving position to prevent movement of the standard to said normal position when it is moved to said second position.
22. In a machine of the class described, the combination with mechanism for operating upon a shoe and power operated actuating means therefor, of a last and shoe support operatively connected with said actuating means for movement longitudinally of

the shoe from a work receiving position to present the supported shoe in operative relation to said mechanism and constructed and arranged for preparatory movement 5 substantially perpendicularly to the plane of the bottom of a supported shoe from a normally elevated position to a position in which said shoe is in the plane for the operation of said mechanism on the shoe, and 10 locking means conditioned by movement of said support, to work receiving position to lock the support with the shoe in said operating plane prior to movement of said support from work-receiving position and automatically 15 operative to release said support and permit it to move to normal elevated position after the operations upon the shoe have been completed.

23. In a machine of the class described, 20 the combination with power operated mechanism for operating upon a shoe and a work carrier operatively connected to said mechanism for movement from a work receiving position to a position to present the work in operative relation to said mechanism, of a 25 shoe and last support mounted on and movable with said carrier and arranged for independent preparatory movement substantially perpendicularly to the plane of the bottom of a supported shoe from a normal position to a second position in which the shoe and last are in the plane for the operation of said mechanism on the shoe, means to lock 30 said support with the shoe in said operating plane prior to movement of the carrier to present the shoe for the operation of said mechanism, and means automatically operative to release said support subsequently and permit it to return to normal position.

40 24. In a machine of the class described, the combination with power operated mechanism for operating upon a shoe and a work carrier operatively connected to said mechanism for movement from a work receiving 45 position to present the work in operative relation to said mechanism, of a last and shoe support mounted on and movable with said carrier and arranged for preparatory depression from a normally elevated position 50 to a second position in which the shoe is in the plane for the operation of said mechanism on the shoe, means normally tending to elevate said support, depressing means operable in the work receiving position 55 of the carrier determinately to depress the support to locate the last and shoe in said operating plane, and means to lock the support in said depressed position preparatory to movement of the carrier from 60 shoe receiving position and to release the support after the operations upon the shoe have been completed.

25. In a machine of the class described, 65 the combination with mechanism for operating upon a shoe, of a shoe support movable

rearwardly to carry the shoe into operative relation to said mechanism, said support being movable also downwardly against yielding resistance to position the shoe in a plane for the operation of said mechanism, locking means for retaining the support in its depressed position, controlling means automatically operative to cause said locking means to release the support for upward movement after the shoe has been positioned 70 in operative relation to said mechanism, and means operative in the return forward movement of the support to return the locking means into position to retain the support when it is next depressed. 80

26. In a machine of the class described, the combination with mechanism for operating with pressure on the bottom of a shoe, of a shoe support movable rearwardly to carry the shoe into operative relation to said mechanism and movable downwardly against yielding resistance to position the shoe in a plane for the operation of said mechanism, locking means for holding the support thus depressed, and controlling 85 means automatically operative after the shoe support has been moved into operative relation to said mechanism to cause said locking means to release the support for upward movement and to oppose increased yielding 90 resistance to downward movement of said support.

27. In a machine of the class described, in combination, power operated mechanism for forming the end of a shoe upper to the 100 end of its last including an end embracing band and end wipers, a last and shoe carrier mounted for bodily movement longitudinally of a shoe toward and from said band and wipers, a last and shoe support mounted on 105 and movable with said carrier, and operating connections between said power mechanism and carrier for moving the carrier into operative relation to the band and wipers, said connections including a yielding element adapting said movement to lasts and 110 shoes of different lengths.

28. In a machine of the class described, the combination with mechanism for operating upon the bottom of a shoe, of a support 115 for a last and shoe arranged to be moved longitudinally of the shoe and last to and from operative relation to said mechanism and constructed and arranged for preparatory adjustment substantially perpendicularly to the plane of the shoe bottom to position the bottom of the supported shoe in the plane for the operation of said mechanism, means conditioned by said preparatory adjustment of the support yieldingly to sustain 120 the support against movement perpendicularly to the plane of the shoe bottom, and means automatically operative subsequently to oppose increased yielding resistance to 125 such movement of the support. 130

29. In a machine of the class described, the combination with mechanism for operating upon the bottom of a shoe, of a work carrier arranged to be moved from a work receiving position into operative relation to said mechanism, a support for a last and shoe mounted on and moving with said carrier and arranged for preparatory adjusting movement substantially perpendicularly to the plane of the shoe bottom to position the bottom of the supported shoe in the plane for the operation of said mechanism on the shoe, means for locking said support against movement from said plane, means normally tending to move the support from said operating plane and effective, in said adjusted position of the support, yieldingly to sustain the support, and means automatically operative to substitute for said yielding sustaining 20 means a sustaining device of greater resistance to support the work against the pressure of said operating means on the bottom of the shoe.
30. In a machine of the class described, the combination with mechanism for operating upon the bottom of a shoe, of a work carrier arranged to be moved longitudinally of a carried shoe from a work receiving position into operative relation to said mechanism, a support for a last and shoe mounted on and moving with said carrier and arranged for preparatory depression from a normally elevated position to a position in which the bottom of the supported shoe is 35 in the plane for the operation of said mechanism on the shoe, a spring normally tending to raise and sustain said support in elevated position, means operative in the work receiving position of said carrier to 40 depress the shoe and its support to said operating plane against the tension of said spring, means co-operating with said shoe support to lock it against upward movement when depressed, a second and stronger 45 spring to sustain said shoe support, and means operative after the carrier has been moved from work receiving position to connect said support with and sustain it by said second and stronger spring against 50 depression by the mechanism operating on the shoe bottom.
31. In a machine of the class described, the combination with mechanism, including upper molding and margin flanging instrumentalities, for forming one end of a shoe upper, of a shoe support movable from a work receiving position to a position to present one end of a supported shoe in operative relation to said forming mechanism 55 and constructed and arranged for preparatory movement with the shoe from a normal position to a position in which the shoe is presented in the plane for the operation of said instrumentalities thereon, and means 60 to lock said support in said operating plane prior to movement of the support from work receiving position to present the shoe for the operation of said forming mechanism.
32. In a machine of the class described, the combination with mechanism, including upper molding and margin flanging instrumentalities, for forming one end of a shoe upper to its last, of a last and shoe support movable from a work receiving position to a position to present one end of a supported shoe and last in operative relation to said forming mechanism and constructed and arranged for preparatory movement with the last and shoe from a normal position to a position in which the shoe is presented in the plane for the operation of said instrumentalities thereon, and means to lock said support in said operating plane prior to movement of the support from work receiving position to present the shoe for the operation of said forming mechanism and subsequently to release said support and restore it to normal position.
33. In a machine of the class described, the combination with mechanism, including upper molding and margin flanging instrumentalities, for forming one end of a shoe upper to its last, of last and shoe supporting and positioning means comprising a work carrier movable from a work receiving position toward and into operative relation to said forming mechanism, heel end and forepart supports for a last and shoe mounted on said carrier and adjustable for length and swing of lasts and constructed and arranged for preparatory movement substantially perpendicularly to the bottom of the shoe from a normal position to a position in which the last and shoe are located in the plane for the operation of said forming mechanism on the shoe, and means to lock said supports in said operating plane prior to movement of the carrier from work receiving position.
34. In a machine of the class described, the combination with mechanism, including upper molding and margin flanging instrumentalities, for forming a shoe upper to one end of a last, of a last and shoe supporting standard movable longitudinally of the shoe from a work receiving position to a position to present the end of the last and shoe in operative relation to said mechanism and constructed and arranged for depression from a normal spring pressed elevated position to a determinate lower position in which the last and shoe are located in the plane for the operation of said mechanism thereon, and means to lock said standard against movement from said depressed position prior to the operation of said mechanism on the shoe.
35. In a machine of the class described, the combination with mechanism, including

upper molding and margin flanging instrumentalities, for forming a shoe upper to one end of a last, of a last and shoe supporting standard movable longitudinally 5 of the shoe from a work receiving position to a position to present the end of the last and shoe in operative relation to said mechanism and constructed and arranged for preparatory depression from a normal spring 10 pressed elevated position to a determinate lower position in which the last and shoe are located in the plane for the operation of said mechanism thereon, and means to lock said standard against movement from said 15 depressed position prior to movement of the standard from work receiving position and to release said standard subsequently and permit it to return to normal elevated position.

36. In mechanism of the class described, the combination of a last and shoe supporting standard mounted for movements in opposite directions substantially perpendicular to the plane of the bottom of a supported 25 last and shoe, and a movable locking member co-operating with said standard and arranged in one position to permit movement of said standard in one of said directions and coincidently to prevent movement of 30 the standard in the opposite direction, and in another position to reverse said conditions for movement of the standard.

37. In mechanism of the class described, the combination of a last and shoe supporting standard mounted for movements in opposite directions substantially perpendicular to the plane of the bottom of a supported shoe, and a controlling member co-operating with and controlling said movements of the 40 standard and movable from a neutral position permitting free movements of the standard in said opposite directions to active positions for locking the standard against movements in the opposite directions respectively.

38. In mechanism of the class described, the combination of a last and shoe carrier mounted for bodily movements in opposite directions, a last and shoe supporting standard mounted on said carrier for movement 50 therewith and arranged for movements relatively to the carrier in opposite directions substantially perpendicular to the plane of the bottom of the supported shoe, a controlling member co-operating with said standard 55 and movable into positions to lock the standard against perpendicular movements in the different directions, respectively and into a third position permitting free perpendicular movements in both directions, and 60 means for shifting said controlling member into said different positions.

39. In mechanism of the class described, the combination of a last and shoe carrier mounted for bodily movements in opposite 65 directions lengthwise of a carried shoe, a

heel supporting standard mounted on said carrier for movement therewith and arranged for movements relatively to the carrier in opposite directions substantially perpendicular to the plane of the bottom of a supported shoe, spring means normally tending to move said standard in one of said directions, a controlling member co-operating with said standard and movable into one position to permit movement of the standard 70 against said spring means and to prevent its reverse movement, movable into a second position to reverse said conditions for movement of the standard, and movable into a third position permitting free perpendicular movement in both directions, and means for shifting said controlling member into said various positions.

40. In mechanism of the class described, the combination of a last and shoe carrier mounted for bodily movements in opposite directions lengthwise of a carried shoe, heel and toe supporting standards mounted on said carrier for movement therewith and for independent shoe positioning movements 85 relatively to the carrier in opposite directions substantially perpendicular to the plane of the shoe bottom, a controlling member for each standard movable to a neutral position 90 permitting free perpendicular movement of the standard in both directions and to another position preventing perpendicular movement of said standard, and means for shifting said controlling members into said different positions.

41. In mechanism of the class described, the combination of a last and shoe carrier mounted for bodily movements in opposite directions lengthwise of a supported shoe, a last and shoe supporting standard mounted on said carrier for movement therewith and for movements relatively to the carrier in opposite directions substantially perpendicular to the plane of the bottom of a supported shoe, a locking member co-operating 105 with said standard and movable from a neutral position permitting free perpendicular movement of the standard in both directions to reverse positions in which it is effective frictionally to grip and lock the standard against movement in the respective opposite directions, and means for moving said locking member into said neutral and reverse locking positions.

42. In mechanism of the class described, the combination of a carrier mounted for bodily movements in opposite directions longitudinally of a carried shoe, a last and shoe supporting standard mounted on and movable with said carrier and constructed and arranged for shoe positioning movements relatively to the carrier in opposite directions substantially perpendicular to the plane of the bottom of a supported shoe, a frictionally gripping locking plate embrac- 120 125 130

ing said standard and mounted for movement from a neutral position permitting free perpendicular movement of the standard in both directions into reverse positions in 5 which it is effective frictionally to grip and hold the standard against movements in the opposite directions respectively, and means automatically operative to move said locking member into said neutral and reverse 10 locking positions.

43. Last and shoe supporting means comprising a carrier, a heel supporting standard and a toe supporting standard mounted on and movable with said carrier and constructed 15 and arranged for shoe positioning movement relatively to the carrier in a direction substantially perpendicular to the plane of the bottom of a supported shoe, means for locking said standards against reverse movement relatively to the carrier, a heel pin mounted on said heel supporting standard for adjustment longitudinally of the shoe, and a toe rest mounted on said toe supporting standard for adjustment trans- 20 versely of the shoe.

44. Last and shoe supporting means comprising a carrier, a heel supporting standard and a toe supporting standard mounted on said carrier and independently adjustable 25 relatively thereto substantially perpendicular to the plane of the bottom of a supported shoe, means for locking said standards in adjusted position, and a toe rest mounted on said toe standard for lateral swinging adjustment and for adjustment longitudinally of a supported shoe.

45. Last and shoe supporting means comprising a carrier, a heel pin supporting

standard and a toe rest supporting standard mounted on said carrier and independently 40 adjustable relatively thereto in opposite directions substantially perpendicular to the plane of the bottom of a supported shoe, means for locking said standards in adjusted position, a heel pin and a toe rest mounted on their respective standards for independent adjustment longitudinally of a supported shoe, and means for effecting and maintaining transverse adjustment of the toe rest to accommodate it to the swing of 50 crooked lasts.

46. Last and shoe supporting means comprising a carrier bodily movable in opposite directions longitudinally of a carried shoe, a heel pin supporting standard and a toe 55 rest supporting standard mounted on said carrier for movement therewith and sustained for independent adjusting movements relatively to the carrier substantially perpendicular to the plane of the bottom of 60 a supported shoe, locking means co-operating with each standard and effective to retain it in adjusted position, a head on the toe rest standard, and a toe rest sustained on said head for adjustment longitudinally 65 of the shoe for length of lasts and arranged for swinging adjustment about an axis substantially perpendicular to the plane of the shoe bottom to accommodate the toe rest to the swing of lasts and shoes. 70

In testimony whereof I have signed my name to this specification.

EDWARD L. BROCK,
Administrator of the estate of Matthias Brock, deceased.
